TOW GUIDE

Robert Harbes Becker, Douglas Lewellyn Johnson, and William Thomas Martin, Pensacola, Fla., assignors to American Cyanamid Company, New York, N.Y., a corporation of Maine

Filed Oct. 26, 1959, Ser. No. 848,843

5 Claims. (Cl. 18—8)

This invention relates to a tow-guide assembly, and more particularly to apparatus adapted to be used in improving post-extrusion, specifically coagulating and handling conditions, of freshly formed, synthetic fiber tow. Still more particularly, this invention relates to a device for guiding and withdrawing synthetic fiber tow from a coagulating bath which comprises a means for maintaining a synthetic fiber tow in uniform contact with the coagulating solution until it is discharged and a discharging means which provides for drawing off the tow with a minimum amount of adhering solution.

In the production of fibers by a wet-spinning process, the fiber- or filament-forming material is extruded as a solution (e.g., a solution of polyacrylonitrile dissolved in a concentrated aqueous solution of a thiocyanate such as calcium thiocyanate) into a coagulating bath through multi-hole spinnerettes which form a fibrous shape. As the spinning solution enters the coagulating bath (e.g., water) it precipitates into gelled multifilaments or tow. It is important that this tow be in contact with the coagulating solution for an adequate time in order to be sufficiently precipitated. After the tow has been in contact with the coagulating solution for the necessary length of time, it is then continuously withdrawn from the coagulating bath for further processing. As the tow is discharged, however, it has been observed that gravity produces a dip in the tow as it comes from the coagulating bath, thereby causing the adhering coagulating solution to travel along with the tow. Some of this adhering solution is eventually re-absorbed by the synthetic fiber tow. This is especially undesirable because of the resulting loss of solution containing valuable solvent, e.g., aqueous thiocyanate solution. In order to overcome these undesirable features, applicants have made the present invention. Nowhere in the prior art is there disclosed a device which is similar to that taught by applicants.

In the past, horizontal rods traversing the direction flow of the tow, or ceramic parts containing small apertures which tend to converge the individual filaments of the tow, were employed as discharging means.

Two notable disadvantages in the use of these prior art devices are that there is considerable damage caused to the filaments themselves and that the converged tow is not sufficiently contacted by the coagulating solution to get complete precipitation. This results in a subsequent fusion of the fibers to one another. Applicants have found that by passing the tow over an arcuate spreading means as it is drawn from the coagulating bath, the tow is maintained in uniform contact with the coagulating solution which is drawn with the fiber tow as it leaves the coagulating bath. After the tow has passed along a sufficient length of this arcuate spreading means, it is then sufficiently precipitated to be transferred to its next step. In order to alleviate the above-mentioned problem of the adhering coagulating solution, applicants found that an upwardly-inclined, arcuate discharging device was effective. This arcuate discharging device not only causes the adhering coagulating solution to be separated from the tow, but also insures sufficient spreading of the tow as it travels across the arcuate spreading means. The use of this device provides for control of the im-

2

mersion time of the filaments in the coagulating solution and independently discharging the solid from the liquid. In addition to these, the solid filaments do not drag on any rough surfaces and the flow of liquid is uniform and, therefore, minimizes breakage of the filaments.

For a better understanding of the present invention, reference may be had to the accompanying drawing in which:

FIGURE 1 is a perspective view of the tow-guide assembly.

FIGURE 2 is a perspective view of the tow-spreading means.

FIGURE 3 is a perspective view of the tow-discharging means.

FIGURE 4 is a perspective view of a sloped weir.

FIGURE 5 is a plan view of the tow-guide assembly, together with the tow coming from the spinnerettes over the tow guide and around the capstans for further treatment.

FIGURE 6 is a side view of the tow being extruded into the coagulating bath from the spinnerettes and being drawn up the tow guide.

The structure of the tow-guiding and discharging assembly is clearly set forth in FIGURES 1-4 of the drawing. The invention as shown in FIGURE 1 comprises an upwardly inclined ramp 1 which is attached at its upper end to a horizontal trough 2. Both the ramp and the trough are bounded on each side by walls 3 which are coextensive with the entire length of each side of the structure. The wall portions of the horizontal trough are raised to maintain the level of solution above the tow and channel the solution over the downstream end. Mounted on the upper end of ramp 1 is approaching planar surface 4 longitudinally extending at an increased 35 inclination from the upper section of the ramp 1. Spanning the upstream end of horizontal trough 2 and extending over a substantial length of the trough is arcuate tow-spreading means 5, which forms a section from a cylinder not necessarily generated from the circle. Longitudinally extending surface 4 terminates in an elliptical or circular arc formed by the plane of surface 4 cutting cylindrical section 6. FIGURE 2 clearly sets forth the structure of the tow-spreading means where the approaching surface is planar. Mounted downstream 40 and spaced from tow-spreading means 5 is an upwardly inclined arcuate tow-discharging means 7, spanning the width of trough 2 and extending at least above the level of tow-spreading means 5. Beneath the discharging means is an open area providing a zone which is in liquid communication with both ends of said trough 2. Located in said zone is an upwardly sloped weir 9 extending the full width of the open area. The terminal end of horizontal trough 2 may be extended on one side with depending element 8 to channel the coagulating solutions which pass over weir 9 into a duct for recycling 45 back to the coagulating baths. (See element 11, FIGURE 5.)

FIGURES 5 and 6 clearly illustrate the use of the present invention for discharging the fibrous tow. These 50 figures show the tow 10 passing up ramp 1, over spreading means 5, discharging means 7 and the coagulating solution return duct 11, around capstans 12 and 12a and on to further treatment.

In operation the tow-receiving ramp 1 is placed in 55 longitudinal alignment to receive the tow as extruded from spinnerette 13. As the precipitated tow 10 is drawn up ramp 1 it carries a certain amount of adhering coagulating solution and continues on to planar surface 4 which merges with arcuate tow-spreading means 5. As clearly 60

illustrated in FIGURE 5, the tow is then spread to provide uniform contact with the adhering solution and is maintained in this condition for a predetermined amount of time which is controlled by the length of tow-spreading means 5, thereby insuring complete precipitation. The tow is then discharged over the upwardly inclined tow-discharging means 7. As the tow travels up the inclined surface of the discharging means, the excess adhering coagulating solution runs back into trough 2 and the tow is then discharged with a minimum amount of adhering solution.

Upwardly sloped weir 9, which may be placed beneath tow-discharging means 7 or further downstream, serves the dual function of maintaining the level of this separated solution and at the same time is sloped in such a way that particles of dirt are automatically discharged over the weir with the excess solution and into the return duct 11 by way of element 8.

The size and shape of applicants' device may vary widely so as to be adapted to various operations which depend on size and type of polymer filament-forming material which is used to produce the fiber. The only critical features of the device are the inclinations or slopes of the ramp 1 and the discharging means 7, and the radius of the arc of the discharging means 7 and tow-spreading means 5. The inclination or slope of ramp 1 cannot be so steep that the newly coagulated tow is distorted or torn, while at the same time it should be sufficiently inclined to keep the trough from flooding. Applicants have found that a slope within the range of from about 15° to 45° from the horizontal is operative but this may be extended in either direction for certain tows which may coagulate either very fast or very slowly. The slope of the discharging means 7 can be varied within the above range, but as the slope is increased there is a tendency for the tow to ride on the discharging edge, and there is also premature separation from the coagulating solution in the trough 2. Preferably the angle should be within the range of from about 25° to 35° from the horizontal. The radius of the arc of the spreading means 6 is not too critical, but it should not be less than about 5 inches. In some instances, the arc may have very large radius if the tow is fragile and is sufficiently spread by the arc of the discharging means 7. In an extreme case the arc may have an infinite radius and the trough would, therefore, have a flat bottom. It is preferred, however, that the radius of the arc fall within the range of from about 5 inches to about 25 inches. The degree of arc for the discharge means 7 is critical and should have a radius within the range of from 10 to 20 inches and preferably within the range of from about 13 inches to about 17 inches. The slope of weir 9 is not critical, but it should not exceed 65° or 75° because the solution at the bottom tends to become static and any dirt present will not be washed over the weir. The height of the weir is, of course, dependent on the size of the tow. The purpose of the weir, as has been indicated hereinbefore, is to insure the level of the coagulating solution above the tow.

The overall dimensions are not critical and may be varied considerably for each individual case. For an efficient design, the tow-discharging means 7 should not be spaced any further than is necessary from the tow-spreading means 5. That is, the tow should not dip off the end of the spreading means but it should extend upward onto discharging means 7. The angle that the approaching surface 4 of the spreading means makes with ramp 1 is negligible and is only an engineering expediency, since it is desirable to have the spreading means a separate unit from the remaining structure for cleaning purposes, etc. Though the other means are also separate units, it is entirely conceivable that the entire device may be constructed as an integral unit.

The above described tow guide may be used in the production of any type fiber or filament formed from a

wet-spinning process. They include all vinyl polymers and copolymers such as acrylics and polyvinyl chloride, polyesters and other condensation type polymers which can be adapted to such a process.

We claim:

1. A tow-guide assembly adapted to guide tow during withdrawal from a coagulating bath comprising an upwardly inclined ramp for receiving and directing the flow of said tow, said ramp being longitudinally aligned with and fixedly attached at its upper end to one end of a horizontal tow-discharging trough, said discharging trough including an arcuate tow-spreading means spanning said one end for maintaining complete contact between the tow and the coagulating solution as the tow with adhering solution is drawn up the inclined ramp and into the discharging trough; an upwardly inclined arcuate discharging means for drawing off said tow with a minimum amount of adhering solution, said discharging means being spaced downstream from said tow-spreading means and providing an enclosed zone; and an upwardly sloped weir located in said zone and whereby excess solution is discharged over said weir.
2. A tow-guide assembly as in claim 1 wherein the upwardly inclined arcuate discharging means has a slope within the range of from about 15° to about 45° from the horizontal.
3. A tow-guide assembly as in claim 2 wherein the arc of said discharging means has a radius falling within the range of from about 10 inches to about 20 inches.
4. A tow-guide assembly adapted for use in the production of a tow of filamentary material by extruding a filament-formable solution into a coagulating bath, said assembly comprising an upwardly inclined ramp for receiving and directing the moving tow, said ramp having mounted on its upper end an approaching planar surface that longitudinally extends at an increased inclination from the upper section of said ramp; a horizontal tow-discharging trough aligned with and fixedly attached at one end to the upper end of said planar surface; an arcuate tow-spreading means spanning one end of said tow-discharging trough for maintaining complete contact between the tow and the coagulating solution as the tow with adhering solution is drawn up the said inclined ramp, and also up the approaching planar surface mounted on the upper end of said ramp, and thence into the said discharging trough; an upwardly inclined arcuate discharging means for drawing off said tow with a minimum amount of adhering solution, said discharging means being spaced downstream from said tow-spreading means and providing an enclosed zone; and an upwardly sloped weir located in said enclosed zone beneath said upwardly inclined arcuate discharging means and whereby excess solution is discharged over said weir.
5. A tow-guide assembly adapted for use in the production of a tow of filamentary material by extruding a filament-formable solution into a coagulating bath, said assembly comprising an upwardly inclined ramp for receiving and directing the flow of said tow, said ramp having mounted on its upward end an approaching planar surface that longitudinally extends at an increased inclination from the upper section of said ramp; a horizontal tow-discharging trough aligned with and fixedly attached at one end to the upper end of said planar surface; an arcuate tow-spreading means spanning one end of said tow-discharging trough for maintaining complete contact between the tow and the coagulating solution as the tow with adhering solution is drawn up the said inclined ramp, and also up the approaching planar surface mounted on the upper end of said ramp, and thence into the said discharging trough; an upwardly inclined arcuate discharging means for drawing off said tow with a minimum amount of adhering solution, said discharging means being spaced downstream from said tow-spreading means, having a slope within the range of from about 25° to 35° from the horizontal, and providing an

enclosed zone; an upwardly sloped weir located in said enclosed zone beneath said upwardly inclined arcuate discharging means and whereby excess solution is discharged over said weir; and a depending element extending on one end of the terminal end of the said horizontal tow-discharging trough for channeling coagulating solution that passes over the aforesaid weir into a duct for recycling back to the said coagulating bath.
